REFRIGERATOR SHELF

Alfred E. Nave, Newburgh, Ind., assignor to
Servel, Inc., New York, N. Y., a corporation of
Delaware

Application July 10, 1940, Serial No. 344,710

2 Claims. (Cl. 211—143)

This invention relates to a shelf for refrigerators especially of the household type.

In household refrigerators there is usually provided in the upper section of the storage compartment a cooling unit and shelves on opposite sides of said unit known as "fly" shelves.

One object of the present invention is to provide improved means for firmly supporting a fly shelf in a refrigerator compartment.

Another object is to provide means for supporting refrigerator fly shelves in a manner to permit easy slideable movement thereof.

Another object is to provide a refrigerator fly shelf that is adjustable in elevation.

In the drawing:

Fig. 1 is a perspective of a refrigerator of the household type having shelves embodying the invention;

Fig. 2 is a horizontal section of the refrigerator cabinet taken on line 2—2 of Fig. 1, and showing in top plan view one of the shelves embodying the invention;

Fig. 3 is a section taken on line 3—3 of Fig. 2 showing in full lines and in dot and dash lines different adjusted positions of the shelf; and

Fig. 4 is a perspective of the shelf.

A household refrigerator 10 comprises a cabinet 11 having a storage compartment 12 and formed by inner metal liner 13 and outer metal casing 14. Casings 13 and 14 are separated by heating insulating material 15 and are trimmed at their front edges with a breaker strip 16. A door 17 in a doorway 18 affords access to the storage compartment 12. In the upper section of the storage compartment 12, a number of fly shelves 19 are provided on opposite sides of a cooling or evaporator unit 20.

Each of the shelves 19 comprises a rectangular border bar frame 22 with a series of parallel wires 23 secured thereto by any suitable means as for instance by welding or soldering and forming a supporting surface for said shelf. One or more of these shelves 19 are slidably supported from a side panel of the inner cabinet liner 13, and for that purpose is secured at one side to a slide 24, slidably and removably mounted in a guide or slideway 25 mounted on said liner panel. The frame bar 22 is U-shaped and has its ends affixed to the slide 24 by any suitable means as for instance by welding. Slide 24 is desirably in the form of a metal panel which is provided with flat parallel side sections 26 offset from the longitudinal center section 27 of said slide and which is so shaped as to permit its manufacture by a simple stamping operation, 55

The guide 25, which is channel shaped, may be made either of metal or of moulded or extruded plastic, and is provided with a flat center section 28 secured to the side panel of the inner cabinet liner 13 by any suitable means as for instance by screws or rivets 29. The longitudinal side sections 30 of the guide channel 25 are shown offset from its center section 28, and are reversely bent to form guide rails for the side sections 26 of the slide 24. The guide grooves defined by these rails 30 are sufficiently wide to permit free slide movement of the slide 24 therein.

The guide channel 25 need not extend the full depth of the storage compartment 12 as shown in Fig. 2, while the shelf 19 with its attached slide 24 extends substantially the full depth of said compartment.

In order to permit changes in the elevation of the shelf 19, the slide 24 and the guide 25 are both symmetrical on opposite sides of their respective longitudinal axes, and said shelf 19 is secured to said slide at a section spaced a substantial distance from the axis of said slide. The elevation of the shelf 19 may thus be changed by merely reversing said shelf as shown in Fig. 3 from the position shown in full lines to the position shown in dot and dash lines, or vice versa.

In order that the shelf 19 present similar interchangeable supporting surfaces, the wires 23 are provided on both the top and bottom of the frame bar 22.

Assuming that it is desired to change the elevation of the shelf 19 from the position shown in full lines to the position shown in dot and dash lines in Fig. 3, the shelf with attached panel 24 is pulled out to slide said panel out of the channel guide 25. The shelf 19 is then reversed, so that the front end of said slide becomes the rear end, and this rear slide end is inserted into the channel guide 25, and the shelf pushed rearward into the storage compartment 12. In this reversed position, the shelf 19 will be in position shown in dot and dash lines in Fig. 3 so that increased storage room is afforded above said shelf. With the shelf adjustable feature, the shelves 19 can be arranged to utilize a great deal more of the available storage space than is possible with fixed shelves.

In either position of the shelf 19, said shelf will be firmly supported by cantilever action to the side wall of the liner 13 so that no additional support for the shelf 19 is necessary.

Various changes and modifications may be

made within the scope of the invention as set forth in the following claims.

What is claimed is:

1. A refrigerator shelf device including a slide symmetrical on both sides of its longitudinal axis, a shelf secured to said slide and spaced from said axis, said shelf including a border frame bar, a series of wires across the top of said frame, and a series of wires across the bottom of said frame, and a horizontal guide for said slide symmetrical about its longitudinal axis to slidably receive said slide in either one of two reverse positions, and having side rail sections overlapping corresponding side sections of said slide to afford a cantilever support for said shelf. 10 15

2. In a refrigerator cabinet, a substantially horizontal slideway on an interior wall of the cabinet, a slide member, a fly shelf secured at one edge to said slide member so that the latter is capable of holding said fly shelf in cantilever fashion, said slideway being open at least at one end to slidably receive said slide member in both right side up and upside down positions of said fly shelf, and said fly shelf being secured to said slide member so that it is nearer one horizontal edge of said slide member than the other, whereby said shelf is located at a different elevation when the shelf and slide member are inverted in said slideway.
